UNITED STATES PATENT OFFICE

WILLIAM A. READY, OF BROOKLINE, MASSACHUSETTS

ELECTRIC-CIRCUIT TUNING DEVICE

Application filed October 23, 1926. Serial No. 143,718.

My invention aims to provide improvements in electric circuit tuning devices particularly, though not exclusively, useful in connection with radio circuits.

Referring to the accompanying drawings, which illustrate a preferred embodiment of my invention:

Figure 1 is a cross-section through front and base panels of a conventional radio receiver, showing in side elevation, a variable air condenser, secured to the panels, a usual dial being shown in dotted lines, secured upon an adjustable shaft made in accordance with my invention;

Fig. 2 is an end elevation of the condenser, the base panel being shown in cross-section and the front panel being omitted;

Fig. 3 is a section on the broken line 3—3 of Fig. 2, showing one means for interlocking the plates of the condenser upon the hollow shaft;

Fig. 4 is an enlarged section on the broken line 4—4 of Fig. 1, showing the formation of the hollow shaft;

Figs. 5 and 6 are sectional views, on the broken line 5—5 of Fig. 3, showing respectively a condenser plate before, and after, portions of the material of the plate have been upset to interlock the plate with the hollow shaft;

Fig. 7 is an enlarged sectional detail on the broken line 7—7 of Fig. 5; and

Fig. 8 is an enlarged sectional detail on the broken line 8—8 of Fig. 6.

In the illustrative embodiment of my invention shown in the drawings, I have employed a variable air condenser of the type generally used in connection with the tuning of a radio circuit. The particular type of condenser illustrated has a set of movable plates 1, shown in the upper part of Fig. 1, and a set of stationary plates 2, shown at the lower part of Fig. 1, and in section, Fig. 2, both sets of plates being supported upon a suitable frame. This frame, as here shown, comprises a base and upright pieces supporting the sets of plates.

The movable plates 1 are carried by a support, in the form of a hollow shaft 3, journaled in bushings 4, threaded into the frame,

as shown in Figs. 1 and 3. The bushings 4 may be screwed in and out of the frame to permit axial adjustment of the group of movable plates 1, in relation to the stationary plates 2, lock nuts 4^a holding the bushings in adjusted positions. The ends of the hollow shaft 3 are frusto-conical and engage internal frusto-conical shaped walls of the bushings to provide a smooth bearing for the set of movable plates 1, as shown in Fig. 3. The hollow shaft 3, (Figs. 3 and 4), is provided with two series of uniformly spaced slits 5, cut into the shaft transverse to the axis thereof, and two internal, longitudinal, grooves 6, parallel with and opening into the axis of said shaft. Each groove 6 intersects or cuts one of the series of slits 5. Each of the movable plates 1, (which may be of any suitable shape), is provided with a slot 7 extending inwardly from one edge thereof, as shown in Figs. 5 and 6. The side walls of the slot 7, (Fig. 5), are spaced the same distance apart as the flat edges of the hub 8 so that, when a plate 1 is slid over the hub, the plate is held against turning relative to the shaft 3. All the plates are thereby held in perfectly spaced alignment. When the plates 1 are placed upon the hubs 8, portions 9 adjacent the side walls of the slots 7 intersect the bore of the shaft 3, as shown in Figs. 3 and 5, and these portions 9 have notches 10 to assist in centering and guiding a suitable tool through the shaft to upset said portions. The tool when inserted in or drawn through the bore of the shaft 3 presses portions (Figs. 3, 6 and 8) of each plate, into the grooves 6, thereby locking the plates so that they cannot slip relative to or become accidentally separated from the shaft 3. The upset portions 11 in the grooves 6 also prevent the plates turning relative to the shaft 3. The above described method of attaching the plates to their support is simple and effective, and may be employed to secure sets of stationary plates.

The frame, see Figs. 1 and 2, includes a pair of upright members 12—12, and spacing means in the form of sheet metal strips 13—13. The ends of the strips are countersunk into the upright pieces 12—12, as shown

in Fig. 2, and fit tightly into the grooves 14, cut in opposite sides of the uprights. The frame parts are suitably held together as by the countersunk screws 15, shown in Figs. 1 and 2. When the parts are thus assembled, the frame is substantially as rigid as a one-piece frame and has the advantages that the strips 13-13 may be made in any suitable length, and the uprights may be spaced to accommodate any given number of plates. Furthermore, the strips 13-13 may be made long enough to connect several upright pieces, so that two or more condensers may be aligned and the movable plates connected by a single shaft. For instance, in the frame construction illustrated, three uprights and two connecting pieces may be provided to support two sets of condenser plates, whereas in a one-piece frame construction, the use of two complete frames would be required to perform the same function. It is easier to assemble and adjust the condenser where the frame is formed of several pieces as illustrated.

25 The condenser illustrated may be secured directly to the front panel 16 as by screws 17, as shown in Fig. 1, and the base panel 18 may be supported by securing it directly to the bottom of the condenser, as by the screws 19.

Heretofore, it has, in many instances, been difficult to connect an operating knob or dial to the shaft of an instrument located behind the panel of a radio receiver, because the shaft is, in many instances, either too long or too short when extended through the panel. In such cases the dial cannot be properly secured to the shaft until there has been some alteration, as by adding a sleeve to make the shaft longer, or cutting off a portion of a shaft. To make such changes unnecessary, I have provided an adjustable shaft 20, of non-conducting material, (Figs. 1 and 3). This shaft telescopes within the hollow shaft 3, and is guided by the bushings 4, as shown in Fig. 3. One end of the shaft 20 passes through the panel 16, and a tuning knob or dial (shown in dotted lines, Fig. 1) is secured thereto. Thus it is a simple matter to loosen the set screw 21 and slide the shaft to fit the dial and then tighten the set screw. The sliding shaft 20 is also useful when connecting several tuning devices together, as a single shaft may pass through a number of hollow shafts and be used to turn all of them.

To prevent interference with smooth sliding action of the shaft 20, relative to the upset portions of the plates, the hollow shaft, adjacent to the slits 5, is provided with a bore 21^a of larger diameter than the diameter of the shaft, so that any slight irregularities, formed when interlocking the plates, will be spaced from the shaft 20. If desirable, the bore may be the same diameter as the shaft 20 providing that the upset portions do not

project into the bore from the grooves, or as illustrated in Fig. 3, one end of the hollow shaft 3, beyond the plates 1, may be bored to fit the shaft 20, the remainder of the bore being larger in diameter.

While I have shown, in Fig. 1, the stationary plates 2 as being secured together by means of spacing elements 22, screws 23 and nuts 24, and mounted in brackets 25 secured to the upright pieces 12-12 of the frame, 75 these plates may be assembled and secured to the frame in substantially the same manner as the plates 1.

My invention is not restricted to the illustrative embodiment shown and described.

Claims:

1. An electric circuit tuning device having a hollow shaft provided with a slit, a tuning plate member carried by said shaft and plate fastening means integral with 85 said plate member, said plate fastening means passing through the slit in the hollow shaft and a portion thereof being upset against the inner face of the bore of the shaft, thereby positively interlocking said 90 tuning plate member with said shaft.

2. An electric circuit tuning device having a hollow shaft provided with opposed slits transverse to the axis of the hollow shaft and intersecting the bore thereof, a plate 95 fitted into the opposed slits in said shaft, an intermediate hub portion provided by said shaft between said slits to support said plate and prevent relative turning thereof and interlocking means integral with said 100 plate and formed by upsetting portions of said plate against the wall of the bore of said shaft to prevent accidental separation of the plate from the shaft.

3. An electric circuit tuning device comprising a hollow shaft, a set of plates carried by said shaft, a plurality of rows of slits formed in said shaft and terminating in spaced relation to provide between them hub means for cooperation with the plates to 105 prevent turning thereof relative to the shaft, longitudinal grooves formed in the wall of the bore of said shaft and intersecting said 110 slits and plate fastening rivet means integral with said plates and having portions thereof 115 upset and pressed into said longitudinal grooves to provide means for locking the plates to the shaft.

4. A tuning device for radio receivers comprising a hollow shaft, and its support, said shaft having a plurality of spaced slits intersecting the bore thereof, plates assembled in said slits and having rivet means intersecting said bore, said shaft having a groove into which the intersecting portions of the 125 rivet means are pressed and upset to secure the plates upon said shaft.

5. An electric circuit tuning device having a frame, said frame including relatively narrow posts having grooves formed in the 130

sides thereof adjacent to their lower ends, a pair of connecting bars fitted into said grooves so as to be countersunk into said posts to resist torsional stresses and contribute rigidity to the frame, fastening means removably fastening said connecting bars to said posts and tuning means supported by means attached directly to said posts independently of said connecting bars.

5 6. An electric circuit tuning device comprising, in combination, a frame, said frame having a pair of end pieces, circuit tuning means supported between and by said end pieces, a pair of spaced connecting pieces of 10 desired length independent of the circuit 15 tuning means, fastening means removably securing said connecting pieces to said end pieces and said connecting pieces and said end pieces being countersunk at opposite 20 edges of the end pieces the one with the other to resist torsional stresses and contribute rigidity to the device.

7. An electric circuit tuning device having a frame comprising a plurality of relatively 25 narrow upright members, tuning means supported between said upright members and detachable spacing means secured to said upright members, fastening means detachably securing said spacing means to said upright 30 members independently of said tuning means for spacing said upright members whereby the space between two upright members is governed according to the length of the spacing means used.

35 In testimony whereof, I have signed my name to this specification.
